RESTORING DEVICE FOR CLINICAL THERMOMETER RECEPTACLES

Kosuke Kashiwagi, Bofucho, Japan

Application January 6, 1932. Serial No. 585,143

1 Claim. (Cl. 206—16.5)

This invention relates to improvements in a receptacle for clinical thermometer, and has for its object to provide a means for rotation of itself in order to have the mercury in the column 5 return to the bulb by centrifugal force.

The drawing illustrates the receptacle of this invention, in which Fig. 1 is a perspective view of the same, and Fig. 2 is a sectional plan thereof.

In the drawing, 1 is a clip attached to an upper 10 part of the receptacle 4 which consists of a long cylindrical body and a cylindrical cap thereon. The clip is made of metal strip curved in C form so as to firmly catch the circumference of the receptacle by its spring action. It has an arm or 15 extension 1—a which co-operates with the wall of the receptacle in order to clamp the latter to the brim of a pocket or the like.

The clip has two perforations 2 on its opposite 20 sides leaving a bridged portion 3 between them as shown in the drawing. The bridged portion 3 is expanded outwards so that a small passage is left between the portion and the surface of the receptacle. Through these small passages is extended a string 5 and its ends are tied together.

25 When the mercury column of a clinical thermometer has risen, and the mercury is to be returned to the bulb, the thermometer, according to this invention, is put in the receptacle as usual, and after the cap is fitted one is to pick up each 30 end of the string 5, and the receptacle should be rotated on the string so as to twist the string on each side of the receptacle. When the string has

been fully twisted, it should be stretched by pulling the ends of the string outwards so that the receptacle is rotated in an opposite direction un-twisting the string, and then the string is further twisted in that direction by inertia till the string 60 is fully twisted again. This action is repeated a few times, then the mercury column in the thermometer will be returned to the bulb due to centrifugal force produced by the rotation.

In order to return mercury in the column 65 to the bulb of a clinical thermometer, the latter is generally swung by a hand. This not only requires considerable troublesome work but also the thermometer may sometimes fly off from the hand. According to my invention, the receptacle can be rotated very easily, and the cost 70 of the clip is not expensive.

What I claim is:

A restoring device for clinical thermometer receptacle comprising a clip secured to the upper 75 part of the receptacle, which clip consists of a metal strip of C section with an extended arm keeping a narrow clearance along the surface of the receptacle, and two perforations are provided on the opposite sides of the clip leaving a bridged 80 portion between the perforations, which portion is expanded outwardly so as to form a small passage between the bridged portion and the surface of the receptacle, and a string inserted through the passages, adaptable for handling of the 85 receptacle.
